UNITED STATES PATENT OFFICE.

MARCUS ARETAS KOSSUTH SHOTWELL, OF NEW PALTZ, NEW YORK.

SQUARE.

1,038,008.

Specification of Letters Patent. Patented Sept. 10, 1912.

Application filed August 27, 1910. Serial No. 579,362.

To all whom it may concern:

Be it known that I, MARCUS ARETAS Kossuth SHOTWELL, a citizen of the United States, residing at New Paltz, in the county 5 of Ulster and State of New York, have invented a new and useful Square, of which the following is a specification.

My invention relates to improvements in steel squares, those in general use by reason 10 of their form, the tongue and blade being one, oftentimes prove burdensome, whereas my object provides a square embodying rare compactness.

My improvement relates to steel squares 15 comprising a blade and tongue as separate parts, the blade being formed by the union of a body and face plate, said body having an interior cross-head groove and channel, the tongue being movably attached to the 20 blade, so mounted as to be maintained at a horizontal position, to rotate upward until perpendicular, and to retreat into the channel. I attain these novel features by the mechanism illustrated in the accompanying 25 drawings, in which—

Figure 1 is an elevation partly in section embodying my invention, defining the interior cross-head groove, and showing the channel, the tongue movably seated in said 30 cross-head groove, maintained stationary. Fig. 2 represents the blade showing the tongue in retreat. Fig. 3 is a plan view of the blade illustrative of the correlation of the tongue with said blade, whereas Fig. 4 35 is an end section of the blade, on the line 4—4, Fig. 3, showing the pocket together with the several attached rivets.

Similar letters refer to similar parts throughout the drawings.

40 Referring to the drawings, "A" designates the cross-head groove. "AA" designates the channel. "B" designates a stop rivet. "C" designates a pivot rivet, provided as a guide and control of the tongue. "D" designates guide rivets. Said several rivets 45 pass through the said cross-head groove, movably attached to the blade.

"E" designates guide slots, said slots forming a mild spring attachment with the guide rivets "D" forming a lock.

"F" designates the slotted center of the tongue, movably engaged with the pivot rivet "C." "G" designates an angular slot

provided in conjunction with the stop rivet "B" as limiting said tongue in its lateral 55 movement, likewise providing freedom for the tongue to rotate.

"H" refers to a thumb nail recess provided for removing the tongue from the blade. "I" refers to cutaway portion of 60 the blade provided for similar convenience.

"J" refers to the rounded corner of the tongue providing freedom in its rotating.

"X" refers to the walls defining the channels in the blade. It is obvious that 65 the tongue by reason of its engagements with the rivets "B" and "D," in conjunction with the shoulders of walls "X," is maintained stationary at right angle position to the blade as shown in Fig. 1, and 70 likewise obvious that when disengaged from said rivets by reason of its being movably engaged with pivot rivet "C," it is free to rotate upward until perpendicular, and retreat downward into the channel as shown 75 in Fig. 3.

Having fully described my invention what I claim and desire to secure by Letters Patent is—

1. The combination in a square comprising 80 a blade provided with an interior cross-head groove and stop rivet and also with a pivot rivet, a tongue provided with an angular slot engaging with said stop rivet, movably seated in said cross-head groove, 85 said tongue having a longitudinal slot to receive said pivot rivet, substantially as set forth.

2. The combination in a square comprising 90 a blade provided with an interior cross-head groove and stop rivet, a tongue provided with an angular slot engaging with said stop rivet, movably seated in said cross-head groove, said blade provided with dual guide rivets in alignment longitudinally of 95 the blade, said tongue provided with dual guide slots in its rear edge, engaging with said guide rivets as means in maintaining said tongue stationary, substantially as set forth.

3. The combination in a square comprising 100 a blade provided with an interior cross-head groove and stop rivet, a tongue provided with an angular slot engaging with said stop rivet, movably seated in said cross-head groove, said blade provided with dual

guide rivets, said tongue provided with dual guide slots, engaging with said guide rivets as means in maintaining said tongue stationary, said blade provided with an interior pocket and pivot rivet, said tongue provided with a slotted center, movably engaged with said pivot rivet, so mounted as to ro-

tate upward until perpendicular and slidably travel in said pocket, substantially as set forth.

MARCUS ARETAS KOSSUTH SHOTWELL.
